UNITED STATES PATENT OFFICE.

WILLIAM H. R. TOYE, OF PHILADELPHIA, PENNSYLVANIA, ASSIGNOR, BY DIRECT AND MESNE ASSIGNMENTS, TO THE MULTI-COLOUR PRINTING COMPANY, LIMITED, OF LONDON, ENGLAND, A CORPORATION OF GREAT BRITAIN.

PRINTING-PRESS.

SPECIFICATION forming part of Letters Patent No. 761,560, dated May 31, 1904.

Application filed November 14, 1895. Serial No. 568,917. (No model.)

To all whom it may concern:

Be it known that I, WILLIAM H. R. TOYE, a citizen of the United States, residing in the city and county of Philadelphia, in the State of Pennsylvania, have invented a certain new and Improved Printing-Press, of which the following is a true and exact description, reference being had to the accompanying drawings, which form a part of this specification.

10 My invention relates to the construction of printing-presses, and especially to what are known as "multicolor-printing" presses, my object being to provide a press of this kind in which the type-forms may be flat and in which 15 the machinery shall be simple, easily gotten at for adjustment, and especially well adapted for good and accurate work.

The nature of my improvements will be best understood as described in connection with the 20 drawings, in which they are illustrated, and in which—

Figure 1 is a side elevation of the press embodying my improvements; Fig. 2, a cross-section on the line $\alpha\alpha$ of Fig. 1; Fig. 3, a 25 cross-section on the line yy of Fig. 4; Fig. 4, a cross-section on the line zz of Fig. 3; Fig. 5, a central longitudinal section through the air-pump, which forms a detail of my mechanism; and Fig. 6 is a side elevation of a portion of the platform D, showing how the rack-sections are secured to it.

A indicates the framing of the machine, which carries tracks or guideways A'.

B is the main driving-shaft, to which are 35 attached fast and loose pulleys, (indicated at B' and B''), B³ indicating a driving-belt. Secured also to the shaft B are spur-wheels B⁴ B⁴ and a cam B⁵. The spur-wheels B⁴ B⁴ engage with and drive gear-wheels C' C', which 40 are secured to a shaft C, to which shaft is also secured a gear-wheel C² and two sprocket-wheels C³ C³, supported on rollers E'. Resting in tracks or guides A' is a table or platform D, which, as shown, is provided with a 45 depending slotted arm D². The platform is adapted and intended to support a series of

type-forms—such as are indicated at G, G', and G²—and on each side of the type-forms are registering surfaces, (indicated at D⁴,) and on one side of each type-form is a sectional rack 50 D³. These rack-sections are in the construction shown adjustable longitudinally, being fastened to the edge of the table by bolts passing through slots, as shown at d⁵, Fig. 6.

E indicates a suitably-supported shaft lying 55 parallel and in the same horizontal plane with the shaft C and having secured to it sprocket-wheels (indicated at E') corresponding with the sprocket-wheel C³ on the shaft C.

F F indicate drive-chains, one running over 60 each pair of sprocket-wheels C³ and E', and F' indicates a pivoted block adapted to slide in the slotted arm D² and having its pivot secured to the two chains F F. It is obvious, of course, that the slotted block will revolve with the 65 chains F F and will by its revolution cause the slotted arm D² and the platform D, to which said arm is secured, to reciprocate, thus giving to the type-forms the desired reciprocating movement. This particular mechanism 70 for actuating the platform D and the type-forms supported upon it is, I believe, novel and forms a feature of my invention; but it will be understood that any device for reciprocating the platform may, if desired, be used 75 in connection with the other features of my invention.

The shaft C not only drives the sprocket-wheels, but through its pinions C² and idler gear-wheels H it drives the shaft I, the gear-wheel H engaging with gear-wheels K³, which 80 are secured to said shaft in a manner to be hereinafter described. The shafts I, I', and I² each support a segmental impression-cylinder, (indicated at J.) This segmental impression cylinder or surface is preferably cast with and as a part of the shaft I, the segmental surface being connected with the shaft by arms J' and a counterweight, as indicated at 85 J⁴, being preferably cast on the back of the shaft to balance the segmental impression-cylinder. On one side of each segmental impres-

sion-surface J, I provide a segmental rack J³, so placed and arranged as to register with and engage the segmental racks D³ when the impression-cylinders come into operative relation to the type-forms carried by the reciprocating carriage or platform D. I also provide each shaft I with flanges J⁵, preferably formed from the same casting as the shaft, as shown, and adapted for the reception of bolts, 10 and on each end of the shaft I place a hub K, having segmental slots K', through which the bolts pass into the collars J⁵, to which they clamp the hubs, while permitting an angular adjustment thereof on the shaft I. Carried 15 by the hubs K are carrier-sheaves K⁴ and also gear-wheels K³, said gear-wheels serving to drive the shafts I, I', and I² and said carrier-sheaves to support and actuate flexible carriers, (indicated at L,) and to which carriers 20 are secured the gripping devices l l, &c., the carrier-sheaves being provided with recesses (indicated at k⁴) at the points where the gripping-bars come in contact with such sheaves. Motion is transmitted from the shaft I to the 25 shaft I' by means of the gear-wheels M² M' M. Mounted on the shafts N are also supported guide-sheaves, around which pass the flexible carriers L, as indicated in the drawings. Motion is transmitted also from the shaft L to 30 the shaft I² by means of similar gearing, (indicated at M³, M⁴, and M⁵) also supported on shafts N, which carry as well guide-sheaves for the flexible carrier-bands. Other guide-sheaves for the carrier-bands are supported 35 and actuated by a shaft P', to which shaft is secured gear-wheels P², driven from the gear K² on shaft I through an idler-pinion P.

The function of the cam B⁵, secured to the shaft B, is to drive the piston of an air-pump 40 (indicated at O) and from which passes a pipe O', connecting, through a pipe O², with the shafts N, all of which are hollow and provided with perforations, as best indicated in Fig. 2, and through which perforations the blast from 45 the air-pump constantly issues. The reason for this construction is that by means of the blast issuing from the shafts N the sheets passing over such shafts are kept from coming into actual contact with them.

50 Q indicates a sheet-delivery device by which sheets of paper are delivered to the grippers on the carrier-bands, and R indicates a receiving device upon which are deposited the sheets after they are taken from the grippers 55 by the take-off roll T.

S S S indicate inking-rolls for the type-forms G G' G².

The action of my improved press is simple, and indeed obvious from the drawings and description already given. Each sheet receives 60 as many impressions as there are printing-couples in the machine in passing once through the machine. At the same time ample pro-

vision is made for inking the type-forms, and a special and very important device consists 65 in the provision made for adjusting the flexible carrier, to which the paper-gripping devices are secured, with reference to the segmental impression-surfaces.

Having now described my invention, what 70 I claim as new, and desire to secure by Letters Patent, is—

1. In a printing-machine, the combination 75 of a reciprocating carriage, a series of flat type-forms supported on and moved by said carriage, a series of shafts and continuously-rotating segmental impression-surfaces corresponding in number with the type-forms and each said impression-surface being adapted to 80 operate in connection with one of the series of type-forms, each said impression-surface being secured to one of the series of shafts, means for actuating the reciprocating table and the rotary impression-surfaces whereby each impression-surface makes one complete revolution contemporaneously with each complete reciprocating movement of the table, carrier-supporting sheaves secured to each shaft on each side of the impression-segments by means 85 permitting their angular adjustment, a continuously-moving endless-belt carrier passing over said sheaves and successively between each type-form and its impression-surface, a series of sheet-grippers secured to 90 said carrier at a distance apart equal to the distance traveled by a point on the impression-surface during a complete revolution and means for supporting and guiding the carrier between the impression-surfaces whereby 95 each gripper and a sheet held therein is made to pass successively between each printing-couple. 100

2. In a printing-machine, the combination 105 of a reciprocating carriage, a series of flat type-forms supported on and moved by said carriage, a series of shafts and continuously-rotating segmental impression-surfaces corresponding in number with the type-forms and each said impression-surface being adapted to 110 operate in connection with one of the series of type-forms each said impression-surface being secured to one of the series of shafts, means including the gear-wheels attached to the carrier-sheaves for actuating the reciprocating table and the rotary impression-surfaces 115 whereby each impression-surface makes one complete revolution contemporaneously with each complete reciprocating movement of the table, carrier-supporting sheaves and gear-wheels securely attached to said sheaves secured to each shaft on each side of the impression-segments by means permitting their angular adjustment, a continuously-moving 120 endless-belt carrier passing over said sheaves and successively between each type-form and 125

its impression-surface and moving at the same speed as the impression-surfaces, a series of sheet-grippers secured to said carrier at a distance apart equal to the distance traveled by 5 a point on the impression-surface during a complete revolution and means for supporting and guiding the carrier between the impres-

sion-surfaces whereby each gripper and a sheet held therein is made to pass successively between each printing-couple.
